[57] CLAIM

The ornamental design for a fishing rod with lighted tip, as shown and described.

DESCRIPTION

FIG. 1 is a perspective view of the fishing rod with lighted tip showing my new design;

FIG. 2 is a top plan view thereof;

FIG. 3 is a bottom plan view thereof;

FIG. 4 is a front elevational view thereof, the rear elevational view being a mirror image of the view shown in this Figure;

FIG. 5 is an enlarged left end elevational view thereof; and

FIG. 6 is an enlarged right end elevational view thereof; and,

FIG. 7 is an enlarged perspective view of the end of the fishing rod illustrating the lighted tip.
